COMBINATION BASIN FOR WASHING AND RINSING DISHES

Rudolph Bernhardt, Evanston, Ill., assignor to Federal Tool Corporation, Chicago, Ill., a corporation of Illinois

Application April 24, 1957, Serial No. 45,874

Term of patent 14 years

(Cl. D4—2)

FIG. 2

Fig. 1 is a perspective view of a combination basin for washing and rinsing dishes embodying my new design; Fig. 2 is a top plan view thereof;

Fig. 3 is a front elevational view of the basin; and Fig. 4 is an end elevational view thereof.

The end not shown is like the end illustrated in Fig. 4. I claim:

The ornamental design for a combination basin for washing and rinsing dishes, substantially as shown and described.
